CURTIS WALTER LESLIE, OF PITTSBURG, PENNSYLVANIA; THERESA A. LESLIE, ADMINISTRATRIX OF SAID CURTIS WALTER LESLIE, DECEASED, ASSIGNOR OF ONE-THIRD TO WILLIAM A. MALINE AND GEORGE J. CAREW, COMPOSING THE FIRM OF MALINE & CAREW, OF YOUNGSTOWN, OHIO.

TROLLEY-WHEEL GUARD.

SPECIFICATION forming part of Letters Patent No. 761,308, dated May 31, 1904.

Application filed November 5, 1903. Serial No. 179,968. (No model.)

To all whom it may concern:

Be it known that I, CURTIS WALTER LESLIE, a citizen of the United States, residing at Pittsburg, county of Allegheny, and State of Pennsylvania, have invented certain new and useful Improvements in Trolley-Wheel Guards, of which the following is a specification.

My invention relates to electric trolley-wheel guards.

10 Heretofore various inventions have been produced to return the trolley to the trolley-wire should it jump from the wire; and it is to this class of devices that my invention particularly relates, my object being to provide 15 an improved and novel trolley-wheel guard of simple and comparatively inexpensive construction, light, strong, and durable, and adapted to automatically return the trolley-wheel to the wire should it jump from the wire.

20 The invention resides in a novel manner of mounting the trolley-wheel in its head and the use of an improved spring for throwing the guard into operative position when the trolley-wheel escapes the wire and also in an improved 25 manner of operating the guard by the trolley-wheel, all as set forth in detail hereinafter and recited in the appended claims.

In the accompanying drawings, Figure 1 is a side elevation of the invention, showing the 30 trolley-wheel on the wire; Fig. 2, a similar view showing the trolley-wheel as jumped from the wire, illustrating how the guards are automatically thrown into action by the springs; Fig. 3, a view taken in the direction 35 of the arrow of Fig. 2, and Fig. 4 a detail of one of the wings of the guard.

The trolley-head 1 is provided with vertical slots 2 in its upper portion, in which the axle 3, carrying the trolley-wheel 4, is adapted to 40 freely slide. Spring-arms 5 bear against the under side of the outer ends of the axle 3 and are secured to the head 1, as shown at 6, said springs having a constant tendency to throw the trolley-wheel upward, as illustrated in 45 Fig. 2.

The guard is composed of two wings 7, pivoted by any suitable pivotal connection 8 to the inner faces of the head 1 and between said inner faces and the outer faces of the trolley-wheel, and said wings are provided with 50 openings or slots 9 of substantially heart shape. The exact shape of these openings could be varied provided the two lobes 10 and 11 are employed to receive the axle 3 when the wings are in their folded and extended positions, respectively, it being understood that the axle 3 passes through the openings 9 in both wings and that both wings are in substantial alinement whether folded or extended.

Numeral 12 designates the trolley-wire. 60

When the trolley-wheel is on the wire, the axle 3 is pressed down to the bottom of slots 2 and lies in the lobes 10, as shown in Fig. 1. When the trolley-wheel jumps the wire, as shown in Fig. 2, the springs 5 throw the axle 65 3 up to the upper end of slots 2, the axle 3 then passing around the pointed portions of the heart-shaped openings 9, swinging the wings 7 on the pivots 8, and finally passing into the lobes 11, whereupon the wings 7 are 70 in the position shown in Fig. 2, and as said wings are divergent, as shown in Fig. 3, the guard finds the trolley-wire and directs the trolley-wheel to the wire again. Immediately 75 the trolley-wheel strikes the wire the axle 3 is pushed down in the slots 2, and the axle travels back into the lobes 10 and the wings 7 are folded, as shown in Fig. 1.

Having thus described my invention, what I claim as new, and desire to secure by Letters 80 Patent, is—

1. In a trolley-wheel guard, the combination with a trolley-head, of a trolley-wheel movable in relation to said head, springs adapted to move the trolley-wheel, a pivoted guard 85 having an opening provided with two lobes, and a member carried by the trolley-wheel which is received in said opening and adapted to play therein and to pass into the respective lobes when in folded and extended positions. 90

2. In a trolley-wheel guard, the combination with a trolley-head, of a trolley-wheel movable in relation to said head, springs adapted to move the trolley-wheel, a pivoted guard having a heart-shaped opening, and a member carried with the trolley-wheel received in said heart-shaped opening, said member being adapted to pass into one lobe of the heart-shaped opening when the guard is folded and to pass into the other lobe of the heart-shaped opening when the guard is extended.
3. In a trolley-wheel guard, the combination with a trolley-head having slots, of a trolley-wheel having its axle slidable in said slots, a spring device for moving the axle in the slots, and a pivoted guard having an opening provided with two lobes, said opening receiving

the axle of the trolley-wheel and the lobes being adapted to respectively receive the axle when the guard is in its folded and extended positions. 20

4. A trolley-wheel guard comprising a trolley-head having slots, a trolley-wheel having its axle slid able in said slots, a guard comprising wings pivoted to the trolley-head and provided with heart-shaped openings receiving the axle, and a spring device for moving the axle in the slots in the trolley-head. 25

In testimony whereof I hereunto affix my signature in presence of two witnesses.

CURTIS WALTER LESLIE.
